FREDERICK MEYER, OF BUFFALO, NEW YORK.

COMBINED DOOR LOCK AND LATCH.

1,415,104.

Specification of Letters Patent. Patented May 9, 1922.

Application filed May 15, 1920. Serial No. 381,623.

To all whom it may concern:

Be it known that I, FREDERICK MEYER, a citizen of the United States, residing in Buffalo, in the county of Erie and State of New York, have invented new and useful Improvements in Combined Door Locks and Latches, of which the following is a specification.

This invention relates to a combined lock and latch for swinging doors and more particularly for the doors used in railway refrigerator cars.

One of the objects of the invention is to provide a combined lock and latch by means of which the door to which it is attached may be hermetically closed so as to prevent all leakage of air through the joints around the door. A further object of the invention is to provide a strong and durable locking latch which may be unlatched from either the outside or the inside of the door, so that a person cannot be imprisoned by an accidental latching of the door. A still further object of the invention is to provide a locking latch which may be easily applied to a door either where said door has already been in use or where the same is new and unused. Further objects and advantages will appear more clearly from the following description and accompanying drawings wherein:

Figure 1 is a horizontal longitudinal section of a part of a door and wall showing the locking-latch applied thereto in plan view and in its locked position. Figure 2 is a horizontal longitudinal section through the locking latch with the same in its latched but unlocked position. Figure 3 is also a similar horizontal longitudinal section but in both the unlatched and unlocked position.

Similar characters of reference refer to like parts throughout the several views.

This improved locking latch may be applied to any swinging door but it is more particularly adapted for use with the door of a railway refrigerator car and will be hereafter so described and treated though of course the same may be otherwise utilized. The vertical outer wall 10 of the refrigerator car is provided with the usual doorway 11 and with the swinging or hinged door 12 which is adapted to engage the adjacent jamb portion of the wall or door frame and is suitably mounted on hinges (not shown) or is otherwise pivoted at one end (the left hand end as it is shown in the accompanying drawings) so as to be able to swing out-

wardly in an arc in the direction indicated by the arrow shown in Fig. 3.

Its inward swinging movement is, of course, limited by striking against the outside face of the wall. For refrigerator work or for other purposes where it is highly desirable to hermetically close the door, and this desired result is most easily secured by merely causing the door to be jammed or closed tightly under the influence of a very heavy pressure. Such a heavy jamming pressure on the closed door is accomplished as follows:

Arranged on the wall adjacent to the edge of the door opening is a base 14, which is provided at its front edge with an outwardly projecting standard 13 and with a pair of lateral base flanges or ears 15, which ears are secured to the wall by means of screws 16 and 160. Pivoted by a pin 17 to the outer end of the said standard 13 is a pressure bar or wedging lever 18 whose inner thickened end is bifurcated at 20 and embraces opposite sides of said standard 13 in a very substantial and strong manner. Secured by screws 21 or otherwise to the door and adjacent to the said standard 13, is a long heavy thrust plate 22 which is preferably provided on its inner end with a pair of thrust faces 23 which are preferably inclined as shown. The wedging lever 18 is provided adjacent to its pivot 17, with a pair of cam faces 24, which are adapted to come into contact with said thrust faces 23 as the lever is turned into the position shown in Fig. 1. This action of the cam faces 24 of the wedging lever causes the door to be closed or pressed backwardly very forcibly against the wall, thereby assuring a tight, hermetic joint between said door and the wall. The frictional resistance between the said cam faces 24 and the thrust faces aids in preventing any alteration in the respective positions of the parts. The outer or thin end of the wedging lever 18 is provided with a longitudinal slot 26 which extends through the lever from one face thereof to the other and is adapted to receive very loosely within its interior, a staple eye or locking post 27 whose legs are suitably secured to the outer end of the thrust plate 22. To lock the refrigerator door when said wedging lever has been closed, a padlock 28 is passed through the outer end of the said staple eye on the outside of the said wedging lever 18. The same result may be obtained however, by any other suitable means as for instance passing

a strip of metal through the said staple eye and securing its ends by means of a compressed lead button as is common practice in railway work. It should be noted that the 5 door is not necessarily held or retained in its tight position by either the padlock 28 or by the frictional resistance of the cam faces 24 against the thrust faces 23. The wedging lever principally retains its position of its 10 "over travel" past the "dead center" position. That is, when the outer thin end of the wedging lever 18 strikes the outer face of the thrust plate 22, a line which is perpendicular to either of the thrust faces 23 at the 15 point of contact thereof with the wedging lever, would pass inside or under the axis of the pivot 17 so that no amount of outward pressure on the door could possibly move or open up the wedge lever. In deed such an 20 outward pressure on the door would actually tend to more tightly close the wedging lever. It has been found in practice however (if the operating parts are substantially or nearly in the geometric relationship of Fig. 1) that the 25 lever will be held firmly in place merely by reason of the frictional resistance of the abutting faces of the parts. It is obvious too that the closed door is only subject to vibration when the car is actually in motion and it is 30 only under such conditions that the accidental opening of the door by reason of vibration need be considered. It is readily understood that when the car is actually in motion, the door is positively prevented from accidentally 35 opening by reason of the padlock 28 aforesaid, because the purpose of a car lock is to keep the same locked while in transit.

The invention also provides for the latching of the door which of course is a very useful adjunct of refrigerator doors inasmuch as 40 such doors must be kept closed at all times except only when actually being loaded or unloaded. The latching arrangement shown in the drawings is as follows:

45 Extending inwardly from the inner side of the front part of the standard 13 is a pair of pivot ears 30 which receive opposite ends of a catch pivot pin 31. Pivoted at its lower end on said catch pivot pin is a 50 catch 32 which is suitably received within the hollow lower interior of said standard. The upper forward part of the catch is provided with a latching tongue or engaging prong 33 whose upper edge is tapered or 55 beveled inwardly and forwardly and whose lower edge projects straight out laterally. The rear end of the catch narrows down to form a long curved tail piece 34 which extends rearwardly and somewhat upwardly 60 and whose outer tip is adapted to be pressed inwardly by the wedging lever 18 in such manner as to unlatch the catch when said wedging lever is turned back from the position shown in Fig. 1 to that shown in Fig. 65 3. The latching tongue 33 of the catch 32

is adapted to co-operate with an abutment 35 which is combined in one integral piece of metal with the afore-described thrust plate 22, the aforementioned thrust faces 23 being formed on opposite longitudinal edges 70 of said abutment 35. The outer face of said abutment is longitudinally straight and flat and is adapted to hook under or engage with the flat under face of the aforesaid latching tongue 33 as shown in Fig. 2. The 75 inner or rear corner of the abutment 35 is however rounded or beveled somewhat so that as the door is closed and the abutment 35 comes in contact with the beveled upper corner of the latching tongue 33, said abutment causes the catch to be "unlatched" or thrown rearwardly into the position shown in Fig. 3 in a manner common to ordinary latches. The latching of the catch is therefore automatic in its action, whereas the unlatching thereof is accomplished by manually moving the wedging lever 18 rearwardly from the position of Fig. 2 to that of Fig. 3. To the rear part of the catch is pivoted a 80 curved draw link 37 whose outer end is bifurcated and whose inner curved end extends inwardly and is guided in the standard in a suitable recessed bearing 40. The countersink or annular recess 41 on the outer side of said bearing 40 is arranged to receive the 85 lower end of a compression catch spring 42 which encircles the curved draw link 37 and bears with its opposite ends against the upper bifurcated end of said draw link and against the bottom of the aforesaid recess 90 41 respectively. Thus the spring tends to always move the catch forwardly into the latching position shown in Fig. 2.

To prevent a workman from becoming accidentally imprisoned or latched in the refrigerator car, a safety or emergency device is provided whereby the catch 32 may be unlatched from the inside of the car. This safety device consists of a chain 43 or other 95 flexible emergency connection, which is fastened at its outer end to the aforesaid draw link 37 and is fastened at its inner end to a sealing disk or washer 44 which is preferably provided with a ring 45 or other suitable means for manually seizing the said disk. The flexible emergency connection or chain 43 is of such a character as to be readily altered in length to suit the particular thickness of the wall of the refrigerator car in which the combined lock and latch is being 100 installed. In the case where a chain is being employed as to the flexible connection 43 the required number of links are merely cut off and the outermost link suitable "bent on" or fastened to the outer side of the disk 44 105 while if the said flexible connection which is being employed is constructed of any other flexible material, it is likewise merely cut to proper length and suitably fastened to the outer face of said disk. The said emergency 110

115

130

connection 43 or chain passes through the refrigerator wall and through the bore of a metal tube 39 which is cut to the desired length and swedged or driven into place, so that the chain is enabled to pass through the refrigerator wall freely and without friction and without liability of becoming tangled up. Furthermore as the walls of refrigerator cars are frequently filled with loose insulating material such as saw dust the use of this chain tube 39 prevents the said insulating material from leaking out of the hollow part of the wall and clogging up the said chain 43 and its appurtenances. The sealing disk 44 serves to hermetically seal the chain tube 39 when the catch is in its outer or normal, latched position so that any flow of air and, therefore any consequent transfer of heat by a leakage is prevented except only when the catch 32 is momentarily unlatched or thrown back whenever it is desired to unlatch the door.

In other words, the normal position of the catch and its emergency chain are, as shown in Figs. 1 and 2, and in this position the chain or the sealing disk is of course prevented from becoming accidentally retained in its drawn out position. Ordinarily, however, in practice the movement of the draw link 37 is taken up by the contraction of the links of the chain or by the contraction of any other flexible connection which may be employed, without disturbing in any way the sealing disk 44 or the ring which is attached to the inner side thereof.

It will thus be seen that the invention not only permits of tightly jamming the door closed and locking the same in this tightly closed position but also serves as an easily operable latch for temporarily latching the door in its closed position. The imprisoning of a workman in the refrigerator car by reason of the accidental latching of the door while he is inside the car, is entirely prevented by the safety or emergency device which is operated by the ring 45. The metal chain tube 39 enables this emergency device to be employed in a refrigerator wall of any thickness and of any sort of internal structure. The nature of the chain or flexible connection 43 is such that it would not ordinarily disturb the position of the sealing disk 44 and certainly very slightly, if at all, so that there is no danger of derangement and furthermore the length of the emergency connection is readily adjusted in length so that the same may be applied to a refrigerator wall of any thickness. It should be noticed too that the whole invention is lacking in delicate fragile parts and is thereby rendered suitable for the heavy duties which are necessarily imposed upon it in refrigerator car work. Furthermore the unlatching and the jamming tight of the door involve the action of a straight line

force, so that the human hand is not necessarily required for its operation, the desired pressure being conveniently obtainable by a movement of the workman's shoulder or foot or by the use of any implement which he may be carrying. Moreover the entire combined lock and latch is simple and reliable in its operation and can be produced at a low manufacturing cost.

I claim as my invention:

1. A combined door lock and latch comprising a catch, a wedging lever provided with a cam face which is adapted, in one position, to tightly jamb the door closed and in another position to operate the said catch. 75

2. A combined door lock and latch comprising a catch, a thrust plate secured to the door, a wedging lever provided with a cam face which is adapted to be tightly jammed against said thrust plate, said lever being 85 also adapted to unlatch the aforesaid catch.

3. A combined door lock and latch comprising a wedging lever provided with a cam face, a catch provided with a latching tongue and adapted to be unlatched by said 90 wedging lever, a thrust plate adapted to receive the thrust of the cam face of said wedging lever, and an abutment adapted to engage with the latching tongue of said catch so as to latch the door. 95

4. A combined door lock and latch comprising a thrust plate and a detent plate adapted to be secured to a door, a standard adapted to be secured to a wall, a wedging lever pivoted to said standard and provided 100 with a cam face which is adapted to be tightly jammed against said thrust plate, and a catch also pivoted to said standard and adapted to be actuated by said wedging lever and provided with a latching tongue 105 which is adapted to engage with the aforesaid abutment.

5. A combined door lock and latch comprising an abutment and a thrust plate adapted to be secured to a door, a standard 110 adapted to be secured to a wall, a catch pivoted to said standard and provided with a draw link, an emergency connection secured at one end to said draw link and passing through the wall to the inside thereof, and a 115 wedging lever also pivoted to said standard and provided with a cam face which is adapted to be jammed forcibly against said thrust plate.

6. A combined door lock and latch comprising a thrust plate and an abutment combined in one integral piece and adapted to be secured to a door, a standard adapted to be secured to a wall, a catch pivoted to said standard and provided with a latching 120 tongue, and a wedging lever also pivoted to said standard and adapted in one of its positions, to jam very heavily against said thrust plate and adapted, in its other position to operate said catch. 125

7. A combined door lock and latch comprising a thrust plate and an abutment combined in one integral piece and adapted to be secured to a door, a standard adapted to be secured to a wall, a catch pivoted to said standard and provided with a latching tongue, a wedging lever provided with a cam face and having two positions, in one

of which the cam face is adapted to jam very heavily against the thrust plate and in the other position, said wedging lever is adapted to unlatch the aforesaid catch, and means for locking said lever in its jamming position.

FREDERICK MEYER.
